John W. Hart and
Lucius Gillihan,

C. A. Snow & Co.

UNITED STATES PATENT OFFICE.

JOHN W. HART AND LUCIUS GILLIHAN, OF IOLA, KANSAS.

ICE-CREAM FREEZER.

SPECIFICATION forming part of Letters Patent No. 442,316, dated December 9, 1890.

Application filed August 29, 1890. Serial No. 363,427. (No model.)

To all whom it may concern:

Be it known that we, JOHN W. HART and LUCIUS GILLIHAN, citizens of the United States, residing at Iola, in the county of Allen 5 and State of Kansas, have invented a new and useful Ice-Cream Freezer, of which the following is a specification.

This invention has relation to ice-cream freezers; and the objects in view are to facilitate freezing the cream, to accomplish the same in a short period of time, and in quantities desired.

With the above and other objects in view the invention consists in certain features of 15 construction hereinafter specified, and particularly pointed out in the claims.

Referring to the drawings, Figure 1 is a perspective of an ice-cream freezer constructed in accordance with our invention. 20 Fig. 2 is a similar view, the lid opened. Fig. 3 is a vertical longitudinal section; Fig. 4, a plan, the cylinder removed; Fig. 5, a detail in perspective of the scraper; Fig. 6, a transverse section of the freezing-cylinder.

25 Like numerals of reference indicate like parts in all the figures of the drawings.

1 designates an oblong box longitudinally divided to form a cover 2, hinged to the box, as at 3, said cover and box having double 30 walls forming a space provided with suitable packings. The box is supported upon legs 4, which are provided with opposite notches 5 for the reception of a sliding shelf 6, which shelf is provided at its rear end with a vertical wall 7, having a dovetailed recess 8 in its upper edge adapted to receive a supporting bar 9, connecting the front and rear legs. The front end of the box is provided with an opening 10, in which is fitted a door 11, hinged 35 at its upper edge to the box, as at 13, and provided with a spring-catch 14 for engagement with a keeper upon the box. Hooks 16 are also secured to the front end of the box and are designed to engage eyes 17, secured 40 to the front edge of the lid or cover, whereby the latter is maintained firmly upon the former. In the bottom of the box there is movably mounted a pan or receptacle 18, the bottom 19 of which is curved concentric with

45 a pair of bearings 20, formed in the upper edges of the longitudinal sides of the box, which bearings correspond with similar half- 50

bearings 21, formed in the lower edges of the longitudinal sides of the cover.

Between the opening in the front end of 55 the box and the adjacent end of the receptacle is located an inclined shelf 23, and above the shelf and over the opening there is secured to the end wall of the box a spring-wire bail 24. This bail is bent to form a transverse bar 25, and its terminals are then coiled, as at 26, to lend resiliency and are disposed at a right angle to the central or bent portion and inserted in or secured to the wall of the box. 65

27 designates a feed-pipe, which passes through the rear wall of the box from the outside, at which point it is provided with a funnel 28 and at its inner end terminates over the receptacle 18. At each side of the feed-pipe, upon spring-arms 29, are secured rubber or other soft wiping-pads or scrapers 30. 70

31 designates the freezing-cylinder, which is provided with double end walls 32, forming a space for the reception of the packing 33. 75 One end of the cylinder is provided with a collar 34, which forms a bearing for the cylinder and acts as an opening for the introduction of the salt and ice. The outer end of the collar has threaded thereon a cap 35. The 80 opposite head of the cylinder has secured thereto a spider 37, from which there extends a bearing-shaft 38, taking into the opposite bearing of the box and cover. The shaft carries outside of the box a gear-wheel 39, which 85 is driven by a small pinion 40, mounted upon a stub-shaft 41, extending from a plate 42, secured to the outer side or exterior of the cover, and from said pinion there extends or radiates a crank-handle 43. The interior of 90 the cylinder is provided at intervals with perforated shelves 44, so that as the cylinder is turned the ice is carried by said shelves to a point opposite the vertical diameter of the same before being let fall to plunge through 95 the water at the bottom of the cylinder to the opposite side of the same, so that a thorough agitation of the ice and a consequent cooling of the water is carried on. By reason of the perforations the ice is strained of water. 100

44* designates a scraper, the opposite sides of which are struck up to form flanges 45, which flanges terminate in hooks 46, located at the upper ends of the same. The upper

end of the scraper is by means of the hooks adapted for engagement with the cross-bar of the bail heretofore mentioned, and is of a width agreeing with the distance between the 5 two inner walls of the freezing-cylinder, while the lower end of said scraper is gradually reduced and passed through the small door at the front end of the box. By means of the spring-bail the upper end of the scraper is 10 snugly pressed against the periphery of the freezing-cylinder.

In operation the freezing-cylinder is first filled with crushed ice and the usual accompaniment—salt—after which the cap of the cylinder 15 is placed in position and the cylinder mounted in the box. The cover being closed and locked, the machine is ready for operation. The shelf under the box is drawn out and a saucer or other receptacle is placed upon the grating 20 47, located over a waste-pan 48, seated in an opening formed in the shelf. A desired quantity of the prepared cream is poured into the funnel, after which the same is closed by a cap 49 and the cylinder turned. The cylinder 25 being cold, the cream adjacent to its periphery between the inner walls or ends thereof is congealed and adheres to the periphery, and is carried by the cylinder to the point of contact thereof with the scraper, by 30 which the cream is scraped and guided down the scraper out from the freezer into the saucer. That portion of the cream partially congealed and adhering to the cylinder opposite the packing between its heads is wiped 35 from the cylinder and drops back into the pan. The operation may be continued as long as desired or until a sufficient quantity of the cream has been frozen, after which the hooks of the scraper may be disconnected and the 40 scraper drawn up and rested upon a lug or screw 50 at the bottom of the opening in the front end of the box, and the small door closed over the opening to prevent the entrance of air and a wasting of the ice by a 45 raising of the temperature within the box.

From the above it will be seen that the cream may be frozen in desired quantities, thus effecting a saving and incurring no waste; also that it saves the frequent opening of the 50 freezer for dispensing cream and the constant exposure of the ice or cooling agent.

Having described our invention, what we claim is—

1. The combination, with the box having an opening and a cylinder revolvably mounted in the box in rear of the opening, and an inverted substantially U-shaped spring-wire bail secured to the box above the opening, of a scraper provided with hooks at its upper end for removably engaging the bail and pressed by the latter upon the cylinder, the lower end of the scraper extending through and terminating outside of the opening, substantially as specified. 55

2. The combination, with the box having the opening, and the revolvable cylinder mounted in rear of the opening and having opposite spring-coils, of the scraper provided with opposite flanges terminating in hooks for removably engaging said bail and pressed by the latter against the cylinder, a set-screw mounted in the lower end of the opening and adapted to support the scraper when the latter is elevated, and a hinged door provided with a fastening mounted over the opening, 75 substantially as specified. 65

3. The combination, with the box, the pan therein, and the cylinder provided with double ends suitably packed, of the opposite wipers yieldingly pressed against the periphery of the cylinder against the packed ends thereof, substantially as specified. 80

4. The combination, with the box, its front legs having notches, and the longitudinal bar oppositely beveled, of the sliding shelf 85 mounted in the notches and provided at its rear end with a vertical wall having a dovetailed recess to receive the bar, substantially as specified.

5. The combination, with the box provided with ways, of the sliding shelf located therein and provided with an opening, a drip-pan mounted in the opening, and a grating mounted over the drip-pan, substantially as specified. 95

In testimony that we claim the foregoing as our own we have hereto affixed our signatures in presence of two witnesses.

JOHN W. HART.
LUCIUS GILLIHAN.
